UNITED STATES PATENT OFFICE.

WILLIAM J. HERBST, OF NEW ORLEANS, LOUISIANA.

FIGURE TOY.

1,001,395.

Specification of Letters Patent. Patented Aug. 22, 1911.

Application filed May 29, 1911. Serial No. 630,051.

To all whom it may concern:

Be it known that I, WILLIAM J. HERBST, citizen of the United States, residing at New Orleans, in the parish of Orleans and State of Louisiana, have invented new and useful Improvements in Figure Toys, of which the following is a specification.

My present invention relates to figure toys; and it has for its general object to provide a toy constituting a miniature theater and comprising figures and means for actuating the figures, whereby one of the figures is made to simulate a dancer in action on the stage and the others the members of a playing orchestra.

Other objects and advantageous features of the invention will be fully understood from the following description and claims when the same are read in connection with the drawings, accompanying and forming part of this specification, in which:

Figure 1 is a perspective of my novel toy as the same appears from the point of view of a person in the audience. Fig. 2 is a detail elevation illustrating a part of the toy as viewed from the back thereof. Fig. 3 is a detail view illustrative of the construction of the dancing figure and the means for imparting motion thereto. Fig. 4 is a detail view illustrating the manner in which the longitudinally-movable bars shown complete in Fig. 2 are connected with the movable members of the figures that simulate the orchestra players. Fig. 5 is a detail horizontal section illustrating the spring motor in plan and also illustrating the manner in which said spring motor is connected with the before-mentioned longitudinally-movable bars; said section being taken in the line 5—5 of Fig. 2. Fig. 6 is a detail view illustrative of the manner in which the tapet comprised in the spring motor is arranged relative to the vibratory bar on which is mounted the platform for imparting motion to the dancing figure. Fig. 7 is a detail view of a part of the motor, hereinafter specifically referred to. Fig. 8 is a detail of the spring motor.

Similar letters of reference designate corresponding parts in all of the views of the drawings.

By comparison of the figures, it will be understood that A is a stage in which is a vertically disposed opening a. The said stage may be provided with suitable scenery

(not shown), and with representations of private boxes (also not shown).

On the face of the wall B that extends downward from the stage A, I prefer to place a picture showing orchestra chairs, occupied or unoccupied, and the members of an orchestra; all but one of the latter figures respectively comprising a swinging arm C, pivoted at e and having on the said arm a pin d that extends rearward through a slot e in the wall for a purpose hereinafter set forth. It will also be noted that the picture of one member of the orchestra comprises instead of a swinging arm, a slide piece C², which slide piece is made to simulate a trombone slide and is provided with a rearwardly extending pin f, disposed in a slot g in wall B. The pins d on the upper of the swinging arms C are connected to the upper longitudinally-movable bar D, while the pins 70 of the lower arms C, as well as the pin f of the slide piece C², are connected to the lower longitudinally-movable bar E. A vertically swinging lever F, Fig. 2, is fulcrumed at h on the back of the wall B, and the upper arm of said lever is connected to the upper bar D, while the lower arm thereof is connected to the lower bar E. Hence when the lever is rocked by means hereinafter described, the bars D and E 80 will be reciprocated and the arms C will be swung to and fro and at the same time the slide piece C² will be reciprocated, with the result that the pictures representing an orchestra will appear in action; the conductor wielding his baton, the violinists their bows, the drummers their sticks, and the trombone player the slide of his instrument.

The dancing figure comprises a body G 95 on which is a head, arms and skirt, and to the lower portion of the said body G are loosely hinged the upper sections H of legs which also comprise lower sections I loosely hinged to the said sections H. The body 100 G of the dancing figure is suspended through a cable J from the top of the stage in such manner as to enable the feet of the figure to rest lightly on a platform K disposed in the before-mentioned opening a in the stage 105 A. Connected at h² to the underside of the stage A is a vibratory bar L, preferably of metal, which bar is connected at its free end to the underside of the platform K. It will also be noted by reference to the draw- 110

ings, that a recess M is provided in the underside of the stage A and in communication with the opening a in order to permit of movement of the vibratory bar upward 5 beyond the plane of the underside of the stage A. On the underside of the bar L is provided a pad N for the engagement of the tappet, hereinafter described, for vibrating or actuating the bar up and down, and here 10 it will be understood that when the bar L is vibrated or rapidly actuated up and down, the platform K will be moved with the bar L and will cause the dancing figure to dance, jump, and turn around after the manner of 15 a ballet performer.

P, Figs. 5 and 6, is a crank connected through a rod Q to the lower end of the lever F, and R is a swinging tappet pivoted at m on a suitable support and backed by 20 a spring n, and having a head p arranged to act against the pad N on the vibratory bar L with a view to vibrating or rapidly moving said bar up and down. Any suitable means may be employed for rapidly 25 rotating the crank P and moving the tappet R against the action of the spring n without involving departure from the scope of my invention as claimed. I prefer, however, to employ for the purpose of rotating 30 the crank P and actuating tappet R, the spring motor illustrated. The said spring motor in addition to a suitable frame S, comprises a shaft T bearing a ratchet disk r, a spring T² connected at one end to the 35 frame S, and wound about the shaft T and connected at its opposite end thereto, a spur gear U loosely mounted on the shaft T and having a pawl u in engagement with the ratchet disk r, a second shaft V bearing 40 a pinion v intermeshed with the spur gear U and also bearing a spur gear W, and a third shaft X having a pinion w and also having a spur gear Y for a purpose hereinafter set forth. The said shaft X carries 45 the crank P and also carries oppositely directed arms Z for striking the tappet R and moving the same against the action of the spring n. By reason of the construction described it will be manifest that when the 50 shaft T is rotated by the expansion of the spring S, the shaft X will be rapidly rotated to rotate the crank P and actuate the tappet R in the manner and for the purposes before described.

55 The spur gear Y on the third shaft X of the spring motor is intermeshed with a pinion a² on a shaft a³, and on the said shaft a³ is also fixed a disk a⁴. This disk a⁴ is normally engaged and held against rotation by a spring strip a⁵ fixedly connected to one side plate of the motor frame S. A screw a⁶ bears in the said frame plate and is adapted at its inner end to engage the said spring strip a⁵. From this it follows 60 that when the spring T² is contracted or

wound up by a suitable key (not shown) applied to the shaft T, and the spring strip a⁵ is held by the screw a⁶ out of engagement with the disk a⁴, the crank P and the swinging tappet R will be actuated by the 70 expanding of the spring T², while when the screw a⁶ is moved outward to permit the spring strip a⁵ to bear strongly against the disk a⁴, the motor will be stopped as will also the movement of the crank P and 75 the tappet R. It will also be understood that through the medium of the screw a⁶ and the spring strip a⁵, the operation of the motor can be regulated, it being simply necessary when it is desired to operate the 80 crank P and tappet R slowly, to move the screw a⁶ outward so as to permit the spring strip a⁵ to bear against the disk a⁴ to a greater or less extent after the manner of 85 a brake shoe.

It will be gathered from the foregoing that my novel toy is reliable in operation, and is calculated to afford considerable amusement to children.

While I have entered into a detailed description of the construction and relative arrangement of the parts comprised in the present and preferred embodiment of my invention, it is to be understood that in the future practice of the invention such changes or modifications may be made as do not involve departure from the scope of my invention as defined in the claims appended.

Having described my invention, what I claim and desire to secure by Letters-Patent, is:

1. In a figure toy, the combination of a stage having a vertically-disposed opening, a support disposed above the stage, a jointed figure loosely suspended from said support, a vertically-movable platform disposed in said opening of the stage and adapted to actuate the jointed figure, a vibratory bar fixed at one end to the underside of the stage and carrying on its free portion the platform, a swinging tappet supported below and adapted to strike against the underside of the bar to vibrate the same, a wall depending from the front of the stage and having slots; said wall bearing on its face simulations of orchestra players, movable pieces forming parts of the simulations and having pins extending rearward through the slots in the wall, longitudinally-movable bars disposed back of the wall and connected to said pins, a lever fulcrumed at an intermediate point of its length and having its arms connected to said bars, and means for actuating said tappet and lever.

2. In a figure toy, the combination of a wall having slots and bearing on its face simulations of figures, movable pieces forming parts of the simulations and having

pins extending rearward through the slots in the wall, longitudinally-movable bars disposed back of the wall and connected to said pins, a lever fulcrumed at an intermediate point of its length and having its arms connected to said bars, and means for actuating said lever.

In testimony whereof I have hereunto set my hand in presence of two subscribing witnesses.

WILLIAM J. HERBST.
